UNITED STATES PATENT OFFICE

EDWARD G. ERICKSON, OF BAKER, MINNESOTA

TRACK-ALIGNING DEVICE

Application filed September 24, 1928. Serial No. 308,022.

This invention relates to track liners and has for an object the provision of means which may be moved over the rails of a track to line or straighten the rails of either straight or curved tracks.

Another object of the invention is the provision of means for adjusting the liner in accordance with the condition of the track, or the degree of the curve, so that the track may be readily and accurately lined and afterward gauged if necessary.

Another object of the invention is the provision of a track liner which may be operated either forward or backward, so as to render it unnecessary to turn the liner around for movement in a reverse direction.

With the above and other objects in view, the invention further includes the following novel features and details of construction, to be hereinafter more fully described, illustrated in the accompanying drawings and pointed out in the appended claims.

In the drawings:—

Figure 1 is a side elevation showing a portion of one end of the liner.

Figure 2 is a top plan view with a portion of the car platform broken away.

Figure 3 is a section on the line 3—3 of Figure 1.

Figure 4 is a diagrammatic view illustrating the relative positions of the liners with respect to the car trucks.

Figure 5 is a diagram illustrating the manner of operation of the liner on a straight track.

Figure 6 is a similar view showing the liner operating on a curved track.

Figure 7 is a section on the line 7—7 of Figure 3.

Referring to the drawings in detail wherein like characters of reference denote corresponding parts, the invention as shown in the drawings comprises a car which may be in the form of a flat car and includes a platform

10. The car is of an appreciable length, being approximately one hundred feet between the trucks 11, by means of which the car is supported for movement over the rails R and R'. The platform is illustrated by

50 broken lines in Figure 4 of the drawings in

order to more clearly show the position of the liners. The trucks are pivotally connected as shown at 12 with the platform 10.

The liners which engage the rails R and R' are arranged in liner units and are spaced longitudinally of the car, one unit L being spaced approximately forty feet from each of the trucks while the other unit L' is spaced approximately twenty feet from the trucks and between the trucks and the units L. The purpose of duplicating these units will be presently apparent.

The units L and L' are of like construction except that they operate upon reverse sides of the rail. Each of these units includes carrier arms 13 and 14 which are vertically disposed and are vertically slideable in guide brackets 14' secured to a beam 15. The lower ends of the arms 13 and 14 carry wheels 16 and 17, the wheels 16 engaging the top of the rails while the wheels 17 engage one side of the rails. The wheels which are carried by the arms 13 may be referred to as a head liner in that they act to straighten out the kinks or irregularities of a rail, while the wheels 17 which are carried by the arm 14 may be termed gauge liners in that they act to position the rail R' with respect to the rail R.

The arms 13 are connected by a lining bar 18 with a beam 19 which extends downwardly and is rigid with one side of the platform 10, connection between the bar 18 and the beam 19 being effected by means of a yoke 20. The central portion of this yoke is adjustably connected to the bar 18 as shown at 21, while the ends of the yoke are pivotally mounted in eye bolts 22 carried by the beam 19. The bar 18 is of sectional formation and the sections are connected by means of a turnbuckle 23, so that the position of the liner may be adjusted with respect to the platform.

The lower edge of the beam 19 is connected with a timber or sill 24 at the opposite side of the car through the medium of rods 25, so that tendency of the lower edge of the beam to move outward will be resisted by these rods 25 and the wheel 17 will be held firmly against the side of the rail.

The arm 13 has secured thereto one end of a gauge rod 26. The opposite end of this rod

100

extends through an opening provided in the arm 14 and has mounted thereon a spring 27, the tension of which may be adjusted by means of a nut 28. The gauge liner may thus be yieldingly though firmly held in engagement with the side of the rail R'.

As previously stated, the arm 14 is vertically movable in the bracket 14' and in order to yieldingly force this arm downward so that the wheel 16 will firmly engage the top of the rail R', cables 29 are employed. These cables have one of their ends secured to the car platform 10 as shown at 30 and their opposite ends secured to the arm 14 as shown at 31. Included in the cables 29 are extensible sections or springs 32. The cables pass beneath pulleys 33 which are carried at the lower ends of brackets 34 which depend from the platform 10. The liners will thus be yieldingly held against upward movement, while limited lateral movement against the action of the spring 27 will be permitted due to play provided between the vertically disposed arms and the guide brackets 14'.

25 The liners are capable of adjustment transversely of the car and for this purpose the beam 15 is provided with longitudinally extending slots 35 which receive bolts 36 carried by a cross beam 37 which is rigid with the platform 10. The beam 15 carries a rack bar 38 and this bar is engaged by a gear 39 carried by a shaft 40 which is mounted in a bearing 41 provided in the platform. A hand wheel 42 is mounted at the upper end of the shaft 40.

35 Each of the units may be adjusted vertically with respect to the car and for this purpose, the arms 13 and 14 are provided with openings 43, while the brackets 14' are provided with openings 44. The units may thus be raised and bolts or pins passed through the openings 43 and 44 to hold the units elevated.

In operation, the car is moved over the track by any suitable power. Assuming that the car is travelling in the direction of the arrow shown in Figure 5 of the drawings, the units L, L' at the forward end of the car are raised out of engagement with the rails. Forward movement of the car will cause the unit L to move the rails laterally as shown in Figure 5. This moves the rails laterally off center, while the unit L' which operates on the reverse side of the rails moves them laterally in an opposite direction, returning them to their proper central position. After this operation, one of the rails, for example the rail R, will be accurately lined, and in the event that the rail R' is positioned to provide proper gauge, this rail may be afterward engaged by the readjustment of the spikes with the ordinary or any preferred gauging operation. Before the lining operation, the liners may be adjusted with respect to the car in accordance with the condition of the track, adjustment being effected through the rack

and gear connection 38 and 39 and the turn-buckle 23.

In lining a curve, after the degree of the curve has been determined, the units L and L' may be properly set through lateral adjustment and the car passed over the rails and the operation previously described performed.

When it is desired to move the car in an opposite direction, the liner units which have been raised are lowered while the liner units at the opposite end of the car are raised. It is therefore not necessary to turn the car around, as this would be a difficult operation in a car of this length.

The invention is susceptible of various changes in its form, proportions and minor details of construction and the right is herein reserved to make such changes as properly fall within the scope of the appended claims.

Having described the invention what is claimed is:

1. A railroad track liner comprising a car having a truck at each end adapted to travel over a track, a pair of transversely spaced rail engaging devices located beneath the car and spaced from the trucks, a second pair of transversely spaced rail engaging devices located beneath the car between the trucks and the first mentioned track engaging devices, and means to adjust the devices transversely of the car.

2. A railroad track liner comprising a car having a truck at each end adapted to travel over a track, means carried by the car and engaging the track to move the rails laterally in one direction, and means also carried by the car and engaging the rails to move said rails laterally in an opposite direction.

3. A railroad track liner comprising a car having a truck at each end adapted to travel over a track, a pair of transversely spaced rail engaging devices located beneath the car and spaced from the trucks, a second pair of transversely spaced rail engaging devices located beneath the car between the trucks and the first mentioned track engaging devices, means to adjust the devices transversely of the car, and means to adjust the rail engaging means laterally with respect to the car.

4. In a railroad track liner, a car adapted to travel over the rails of a track, transversely spaced rail engaging devices carried by the car and engaging the top and one side of one of the rails, transversely spaced rail engaging devices carried by the car and engaging the top and one side of the other rail, the second mentioned devices engaging the side of the rail opposite that engaged by the first mentioned devices, and means to adjust the devices transversely of the car.

5. In a railroad track liner, a car adapted to travel over the rails of a track, transversely spaced rail engaging devices carried by the car and engaging the top and one side of one of the rails, transversely spaced rail

engaging devices carried by the car and engaging the top and one side of the other rail, the second mentioned devices engaging the side of the rail opposite that engaged by the first mentioned device, and means to yieldingly hold the rail engaging devices of one rail in engagement with said rail.

6. In a railroad track liner, a car adapted to travel over the rails of a track, transversely spaced rail engaging devices carried by the car and engaging the top and one side of one of the rails, transversely spaced rail engaging devices carried by the car and engaging the top and one side of the other rail, the second mentioned devices engaging the side of the rail opposite that engaged by the first mentioned devices, each of said devices including transversely spaced vertically disposed carrier arms, rightangularly disposed wheels carried at the lower ends of said arms, means to mount the arms for vertical movement, means connecting the arms, and means to adjust the arms transversely of the car.

7. In a railroad track liner, a car adapted to travel over the rails of a track, transversely spaced rail engaging devices carried by the car and engaging the top and one side of one of the rails, transversely spaced rail engaging devices carried by the car and engaging the top and one side of the other rail, the second mentioned devices engaging the side of the rail opposite that engaged by the first mentioned devices, each of said devices including transversely spaced vertically disposed carrier arms, rightangularly disposed wheels carried at the lower ends of said arms, means to mount the arms for vertical movement, means connecting one of the arms with the car to force the wheels carried by said arm against one of the rails, means yieldingly connecting said arm with the other arm to force the wheels carried thereby against the other rail, and means to adjust the arms transversely of the car.

45 8. In a railroad track liner, a car adapted to travel over the rails of a track, transversely spaced rail engaging devices carried by the car and engaging the top and one side of one of the rails, transversely spaced rail engaging devices carried by the car and engaging the top and one side of the other rail, the second mentioned devices engaging the side of the rail opposite that engaged by the first mentioned devices, each of said devices including transversely spaced vertically disposed carrier arms, rightangularly disposed wheels carried at the lower ends of said arms, means to mount the arms for vertical movement, a lining bar connecting one of the arms with the car to force the wheels carried by said arm against one of the rails to line said rail with respect to said car, means to yieldingly connect said arm with the other arm to force the wheels carried thereby against the

other rail, and means to adjust the arms transversely of the car.

9. In a railroad track line, a car adapted to travel over the rails of a track, transversely spaced rail engaging devices carried by the car and engaging the top and one side of the rails, transversely spaced rail engaging devices carried by the car and engaging the top and one side of the other rail, the second mentioned devices engaging the side of the rail opposite that engaged by the first mentioned devices, each of said devices including transversely spaced vertically disposed carrier arms, rightangularly disposed wheels carried at the lower ends of said arms, means to mount the arms for vertical movement, means connecting the arms, and means to yieldingly force the rail engaging devices downward.

In testimony whereof I affix my signature. EDWARD G. ERICKSON.
